DORRIEN G. MOON, OF LARCHMONT, NEW YORK, ASSIGNOR TO CONTINENTAL PAPER
AND BAG CORPORATION, OF NEW YORK, N. Y., A CORPORATION OF NEW YORK

DIGESTER SUPPORT

Application filed August 1, 1929. Serial No. 382,683.

My invention relates to an apparatus for cooking wood or other fibrous materials used in paper making, usually designated a "digester", and more particularly, to a support therefor. It has for its object to provide an improved digester support of sturdy construction capable of withstanding the continued and hard usage to which such digesting apparatus is subjected. A further object of the invention is to eliminate certain disadvantageous factors contributing to the failure, within a comparatively short space of use, of the digesters now in use. The continued vibration attendant the operation of the cooking apparatus or digester, tends to soon weaken the structure supporting it, particularly at the points at which said digester is joined, usually by riveting, to the support. Such riveted joints between digester and support are weakened or are very easily broken down with the result, usually, of a leaking joint through which the contents of the digester may trickle and further disintegrate the joint by the action of the chemicals used therein. The apparatus of the instant invention is designed to overcome these defects by the elimination of the riveted joint between digester and support and presents a new and improved digester supporting structure. The invention resides in a combination of elements, the novel features whereof will appear more particularly from the description hereinafter and from reference to the accompanying drawings forming part of this specification.

In such drawings, Fig. 1 is a plan view of my improved support with the digester in position; Fig. 2 is a front elevation thereof; Fig. 3 is an enlarged plan detail of one of the cradle brackets of the support; and Fig. 4 is an enlarged detail in elevation of one of the columns with a somewhat modified form of bracket. Fig. 1 may also be described as a section along line 1—1 of Fig. 2.

Referring more particularly to the drawings, the digester shell 10, which may be of any shape and construction, the usual "cone type" being illustrated, is positioned on cast steel brackets 11, having an inner surface configuration corresponding to the curv-

ature of the digester shell. The brackets 11 have a contact surface at an angle corresponding to the angle of inclination of the side of the vessel which they support. These brackets are mounted on cast iron columns 12 of any suitable number, four being usually sufficient to form a rigid supporting structure. The size and weight of the digester will, of course, in all cases govern the number of supporting columns and their dimensions. The columns 12 terminate, at their lower extremities, in foundation plates 13 having the usual angular ribs 14. At their upper ends, a channel platform 15 presents the supporting surface on which the brackets 11 rest and to which the latter may be secured by bolts 16 having their heads 17 within the hollow interior of the brackets, and nuts 18 applied thereto within the channels of platforms 15 into which said bolts extend.

Each of the brackets 11 is provided with an integral pair or plurality of pairs of anchor members 19 for engaging the threaded ends of tie-rods 20. Nuts 21 are threaded on such tie-rods before the latter are positioned within such anchor members, nuts 22 being applied thereto thereafter. All of said nuts 21 and 22 are then tightened so as to connect the brackets 11 rigidly to each other in fixed spaced relationship and into a unitary structure by means of tie-rods 20 as will clearly appear from the drawings. The anchor members are at an angle to each other depending upon the number of supporting columns used, as will also be obvious from an inspection of the drawings. The use of a double row of anchor members, as shown, further increases the rigidity of the supporting structure and contributes to its capacity to withstand hard usage.

As shown in Fig. 3, the bracket surface engaging the digester shell is decreased by a depression 23 presenting only the edge portions 24 and 25 for contact with the shell. This construction yields an advantageous "cradling" effect in supporting the digester whereby a better contact between digester and bracket is obtained obviating the necessity of having the inner surface configuration of the bracket correspond exactly to the

curvature of the digester and eliminating a possible point contact instead of the desired surface contact.

It will be apparent from a consideration of the structure hereinabove described that the bracing construction forming an important feature of my invention results in certain definite advantages not present in existing apparatus such, for instance, as employ riveting as a means of joining the digester shell to its supporting structure. In the course of cooking the materials such as wood, rags, and similar fibrous materials, certain chemical substances, either acid or alkaline, are placed within the digester. The use of such chemicals necessitates the provision of the digester with a lining of a material which will resist the action of such chemicals. Through the continued vibration attendant on the operation of the digester, any kind of joint between the digester shell and support, and particularly a riveted joint, becomes loosened permitting such loosened joint structures to destructively affect the lining of the digester, tending towards its final breaking down. Cracks begin to appear in such lining through which the acid or alkaline substances may trickle and further disintegrate, by their corrosive action on the metal of both digester and supporting structure, the entire apparatus. By bracing the supporting structure independently of the digester and providing a "cradle" for the digester shell in which it rests and which is not affected by its vibration, as herein described and illustrated, I obtain a construction of digester supporting apparatus which is possessed of particular strength, durability, and rigidity capable of withstanding the continuous shocks and pounding to which the digester shell and support is necessarily subjected. Furthermore, the simplicity of the assembly of my braced supporting structure facilitates repairs that may be necessary either to the digester itself or to the supporting apparatus. The digester may be easily lifted from the supporting structure and repairs made thereon. Any form of joint between digester and support, particularly the riveting means now employed precludes repairs on the digester independently of the supporting apparatus.

While I have described and shown a particular embodiment of my invention, it is obvious that various changes in design and construction of the various parts may be made without departing from the spirit of the invention.

I claim:

1. A digester support comprising a plurality of columns, brackets mounted thereon for supporting the digester shell and tie-rods connecting said brackets.
2. A digester support comprising a plurality of columns, brackets detachably mounted thereon for supporting the digester

shell and tie-rods connecting said brackets.

3. A digester support comprising a plurality of columns, brackets mounted thereon for supporting the digester shell and having contact surfaces corresponding in configuration to the curvature of the exterior of said shell, and tie-rods connecting said brackets. 70

4. A digester support comprising a plurality of columns, brackets mounted thereon for supporting the digester shell, a plurality of anchor members on each of said brackets, and tie-rods for connecting the anchor members of adjacent brackets. 75

5. A digester support comprising a plurality of columns, brackets mounted thereon for supporting the digester shell, a plurality of anchor members on each of said brackets, and tie-rods threaded at both ends and adapted to receive nuts for engaging them to said anchor members. 80

6. The combination, with a digester, of a support therefor comprising a plurality of supporting columns, brackets mounted thereon to cradle the digester shell, and tie-rods connecting said brackets. 90

7. A digester support comprising a plurality of vertical columns terminating at their upper ends in brackets supporting the digester vessel between said columns to move freely thereon, and tie-rods for connecting said brackets and adapted to keep said brackets in fixed spaced relationship. 95
